UNITED STATES PATENT OFFICE.

GEORGE L. K. MORROW, OF DETROIT, MICHIGAN.

DESIGN FOR A BICYCLE-FRAME.

SPECIFICATION forming part of Design No. 28,550, dated May 3, 1898.

Application filed November 22, 1897. Serial No. 659,522. Term of patent 14 years.

To all whom it may concern:

Be it known that I, GEORGE L. K. MORROW, a citizen of the United States, residing at Detroit, in the county of Wayne and State of Michigan, have invented and produced a new and original Design for a Bicycle-Frame, of which the following is a specification, reference being had to the accompanying drawing, forming part thereof.

This design relates to a bicycle-frame; and it consists in a bicycle-frame distinguished by its peculiar shape, as will be hereinafter described and claimed.

The main feature of the design consists in the employment with an ordinary trussed frame of an angularly-arranged connecting portion which divides the trussed frame into two parts, one of which is substantially triangular and the other of an irregular polygonal form, while the said connecting parts form with the main-frame parts substantially a figure 4, lying between and above the triangular and polygonal parts of said frame.

In the drawing, *a*, *b*, *c*, and *d* represent a trussed frame.

efg is the connecting portion, which crosses the trussed frame at the points *e* and *f* and divides the trussed frame into the triangular

portion *efd* and the polygonal portions *ab* *cfe*. The connecting portion *efg* is also 30 extended from *g* to *c*, so as to form with the trussed frame in turn substantially a figure 4, *c g f e*, which lies between the triangular and polygonal portions and partly above the same.

In addition to the above main feature of the design I form the frame at the point *d* with a circular hub or sleeve having on the interior thereof a series of teeth or projections *h*. In addition to the above I also form 40 the trussed frame so that the parts from *a* to *d* and from *c* to *d* are bifurcated, the connecting portion *ef* extending through the forks of said bifurcations.

Having thus described my invention, I 45 claim—

The design for a bicycle-frame, substantially as herein shown and described.

In testimony whereof I have hereunto set my hand this 11th day of November, A. D. 50 1897.

GEORGE L. K. MORROW.
